UNITED STATES PATENT OFFICE.

ABRAHAM J. SYPHER, OF IRON MOUNTAIN, MISSOURI.

PISTON-ROD PACKING.

SPECIFICATION forming part of Letters Patent No. 426,399, dated April 22, 1890.

Application filed December 26, 1889. Serial No. 335,090. (No model.)

To all whom it may concern:

Be it known that I, ABRAHAM J. SYPHER, of Iron Mountain, Missouri, have made a new and useful Improvement in Piston-Rod Packing, of which the following is a full, clear, and exact description.

The improved packing is a peculiar combination of rings or parts of rings, whereby what is termed a "ring-packing" which wears evenly is obtained, substantially as is herein-after described and claimed, aided by the annexed drawings, making part of this specification, in which—

Figure 1 is a view of a drill having the improved packing. The drill-chuck, piston-rod, and piston are shown in elevation, the cylinder in section, and one of the halves of the cylinder-head is removed, and only that portion of the drill which is more immediately in connection with the improvement is exhibited; Fig. 2, a side elevation of the drill. The view is at right angles to that of Fig. 1. Fig. 3 is a cross-section on the line 3 of Fig. 2; Fig. 4, a view in perspective of the outer one of the packing-rings, and Fig. 5 a view in perspective of the inner one of the packing-rings. The last two views are upon an enlarged scale.

The same letters of reference denote the same parts.

The improvement is shown applied to a drill A, which, saving as it may be modified or supplemented by the improvement, is of a familiar form, its cylinder being shown at B, its piston at C, piston-rod at D, and its drill-chuck at E; and F F' represent the two halves of the cylinder-head at that end of the cylinder which is toward the chuck. The bolts f f serve to unite the halves F F', and G G represent the tie-rods which unite cylinder and its heads, one of which heads is not shown.

The improved packing is composed of an inner ring H and an outer ring I, constructed and combined as follows: The inner ring is in four parts $h\ h'\ h^2\ h^3$. The outer ring is in two semicircular parts *i.e.* They are formed by dividing the ring I in the direction of its length.

The four parts of the ring H are produced by dividing the ring both in the direction of

its length and crosswise, and particularly as follows: The parts $h\ h'\ h^2\ h^3$ are each substantially semicircular. The part h' may have no projection. The part h is notched at h^4 . The parts $h^2\ h^3$ have each a projection h^5 , and when the parts are combined to form the ring H the projections $h^5\ h^5$ enter the notch h^4 , and the joints $h^6\ h^6$, between the parts $h'\ h'$, are out of line with the joints $h^7\ h^7$ between the parts $h^2\ h^3$. The cylinder-head F F' is recessed at f' to receive the rings H I, which are applied to the piston-rod, as shown in Figs. 1 and 3, the ring H encircling the piston-rod and the ring I encircling the ring H. The cylinder-head is further recessed at f^2 to form a steam-passage encircling the outer ring I. The passage f^2 is connected with the interior of the cylinder B by means of one or more passages $f^3\ f^3$, so that the steam from the cylinder can pass into the passage f^2 and there act to compress the outer ring upon the inner ring, and the inner ring in turn upon the piston-rod.

The special advantage derived from the described construction is this: The inner ring H can in the operation of the drill turn around upon the piston-rod freely, and can also turn around within the outer ring I, and in consequence the ring H wears smoothly upon the piston-rod, and the two rings wear smoothly upon each other, and a very efficient packing is readily obtained. The recess f' confines the rings H I endwise in place, as shown.

Owing to the described manner of constructing and combining the four parts of the inner ring, the joints being the parts of the outer ring can never come into coincidence with all of the joints of the inner ring at once.

I claim—

In a metal packing for a shaft, the combination, with the inner divided ring H, composed of the lower semicircular section h , having the notch h^4 in its upper edge midway of its ends, the lower semicircular section h' , with its ends abutting against the adjacent ends of the section h , and the two upper abutting semicircular sections $h^2\ h^3$, breaking joints with the lower sections and provided

with adjoining projections h^5 , that enter the notch h^4 and prevent the upper sections from rotating on the lower sections, of a suitable outer ring having a length equal to that of 5 the inner ring surrounding the said sections and composed of two similar semicircular abutting sections, substantially as specified.

Witness my hand this 16th day of November, 1889.

ABRAHAM J. SYPHER.
